Des. 232,626
Patented Sept. 3, 1974

232,626

PITOT TUBE COVER

Harry S. Smallwood, 4125 Timberline Drive,
San Jose, Calif. 95121

Filed Dec. 1, 1972, Ser. No. 311,295

Term of patent 7 years

Int. Cl. D12—99

U.S. Cl. D12—81

FIG. 1 is a perspective view of a pitot tube cover showing my new design;

FIG. 2 is a right side view of the pitot tube cover of FIG. 1; and

FIG. 3 is an end view of the pitot tube cover of FIG. 1 with an element omitted for ease of illustration.

I claim:

The ornamental design for a pitot tube cover, as shown and described.
